UNITED STATES PATENT OFFICE

1,995,218

FOUNTAIN PEN

George Howard Osterhout, United States Marine
Corps, Parris Island, S. C.

Application July 2, 1934, Serial No. 733,502

2 Claims. (Cl. 120—46)

The present invention relates to improvements in fountain pens, and relates to certain improvements over my prior similarly entitled Patent No. 1,647,882, granted November 1, 1927.

It is an object of the present invention to provide a device for manipulating the rubber bulb or nipple in the prior patent, thereby dispensing with the need of removing the cap and squeezing the nipple with the fingers.

The invention has for a further object the production of a simple form of operating mechanism for the nipple in which the parts are few and reliable in operation.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a side elevation, with parts broken away and parts shown in section, of an improved fountain pen constructed according to the present invention.

Figure 2 is a fragmentary longitudinal section taken on an enlarged scale and showing the parts in locked position.

Figure 3 is a similar view showing the plunger and nipple in expanded position.

Figure 4 is a cross section taken on the line 4—4 in Figure 2.

Figure 5 is a similar view taken on the line 5—5 also in Figure 2.

Figure 6 is also a cross section taken on the line 6—6 in Figure 2.

Figure 7 is a perspective view of the spring.

Figure 8 is a similar view of the plunger, and

Figure 9 is a cross sectional detail of a modified form of plunger.

Referring more particularly to the drawing, 8 designates the barrel of the pen which is open at one end and internally threaded to receive the plug 9 containing the pen nib and point 10. The nib and point are provided with the ink opening 11 and passage 12, such passage extending through the plug 9 and in communication with the interior ink space of the barrel 8. The plug is shouldered at 13 to take against the end wall of the barrel 8, and threads 14 may be provided upon the exterior wall of the barrel 8 to receive complementary threads upon a cap (not shown, but illustrated at 15 in my prior patent aforesaid) usually employed for housing and protecting the pen point.

55 The plug or nib is further provided with a pas-

sage 16 opening downwardly to the atmosphere and upwardly into the tube 17 which extends up through the barrel 8 and through the upper closed end 18 of said barrel. The upper end of the tube 17 is in communication with the interior space of the rubber or other bulb or nipple 19. This nipple may be of appropriate size and shape and has its rim portion stretched or expanded across the shouldered upper portion 20 of the barrel end 18. The tube 17 is bent at right angles at its upper end and has its terminal end 21 disposed downwardly within a valve chamber 22 which opens upwardly freely into the interior space of the bulb 19.

In the valve chamber is a ball or pellet valve 15 23 adapted to vibrate between the open end of the tube terminal 21 and a seat 24 formed at the bottom of the cavity or chamber 22. A port 25 leads from the cavity 22 downwardly past the seat 24 into the interior ink space of the barrel 8. 20

The foregoing construction is that substantially illustrated and described in my prior patent aforesaid, except that the illustration in the present case departs more or less from the patent illustration in the matter of proportions and sizes 25 of parts and particularly in the shape and size of the bulb or nipple 19. Such shape and size of the nipple, as herein illustrated, are arranged to cooperate to a higher degree with the manipulating mechanism now to be described.

The end wall 18 of the barrel 8 is provided with a second shouldered portion 26 stepped to wider diameter than the nipple receiving shouldered portion 20. Such shouldered portion 26 is adapted to snugly receive thereon the rim portion of a protecting cap 27, which houses the bulb or nipple 19, and also contains the operating mechanism which consists in part of a flat or leaf spring 28. Such spring may be of the substantial shape illustrated in Figure 7, being provided with a slightly crimped portion 50 at its upper end, with the leaf of the spring slightly curved inwardly when in operating position. The crimped part 50 forms a fulcrum for engaging against the wall of the opening 36 as shown in Figure 3.

This spring is of extreme thinness, of non-corrosive composition, and of great flexibility, completely free at both ends, and by its nature and shape retains itself in place by pressure, the inner or lower end engaging in the circular groove 33 and the upper crimped end of this spring 31 resting within a recess in the bottom of a plunger 32. The foot 30 is adapted to rest within the annular groove or boot 33 formed in the interior wall of the protecting cap 27 on line with top 55

of part 18. The plunger cavity 34 is formed with an inclined wall 35 adapted to cooperate with the bent end of the leaf spring 28. Such plunger 32 fits snugly through the upper open end 36 of the protecting cap 27 and is formed with a rim 37 at its upper exposed end for resting upon the top of the cap 27 whereby the plunger 32 may be readily turned, causing it to unlock and be raised, or pushed upward by action of spring 28, when 10 it may be manipulated by alternating pressure, and release, up and down in the cap 27.

Bayonet slots 38 are formed in the plunger for receiving a pin 39 extending diametrically through the cap 27, as shown in Figure 4.

15 In the operation of the device, the parts are normally in the position shown in Figure 2 with the plunger 32 locked in the inner position by reason of the angular portions of the bayonet slots 38 engaging the cross pin 39. This condition is achieved by forcing the plunger 32 inwardly with respect to the cap 27 and then rotating same by turning the rim 37 in a clock-wise direction.

When the pen is to be filled, the plunger 32 is 25 rotated in the reverse direction whereby the slots 38 are brought to the position shown in Figure 3 with reference to the cross pin 39. The leaf spring 28, acting within the annular groove 33 and also on the recessed place within the base of the plunger 32, automatically projects the plunger upwardly and outwardly and allows the rubber nipple 19 to expand. As the nipple is expanded, it will tend to create a partial vacuum within the same, raising the pellet valve 23 against the open 35 end 21 of the tube 17, and preventing atmospheric air from being sucked through the tube 17 into the interior space of the nipple 10; but requiring that air from the interior or ink space of the barrel 8 be drawn up through the port 25 and chamber 22 into the bulb space, thus tending to 40 expel the air from the ink space of the barrel 8, such that the pen point and nib being immersed in a bath of ink, such ink will be drawn into the ink space of the barrel 8 through the opening 11 and passage 12.

When the plunger 32 is on the next stroke forced inwardly (downward)—due to base 30 of the spring being engaged in the annular groove 33, and the upper end 31 pressed upwardly and laterally within the recess 34—the leaf of the 50 spring 28 is arched inwardly, and, depending upon its flexibility, partially or wholly collapses the bulb or nipple 19 thus driving the air out of the same, first causing the pellet valve to be reseated against its seat 24.

The air from the interior of the bulb will thus not be permitted to be forced back through the barrel 8, but will be driven out through the now open end 21 of the tube 17 and into the atmosphere at and about the pen plug 9.

60 These manipulations of the plunger 32 are repeated as many times as may be required to draw in a sufficient charge of ink from a well or bath. The same alternating depressing and releasing of the plunger 32 will cause the barrel to empty when the nib and point are held out of the fluid container.

The device is constructed so as to be readily taken apart and reassembled after cleaning or

the replacement of parts. A rivet, such as shown at 40 in Figure 6, is adapted to hold the cap 27 in place and with it the entire assembly. This rivet can be readily knocked out to permit of the lifting off of the cap 27 with the other parts of the manipulating device.

Referring more particularly to Figure 9, the plunger in this case is devoid of bayonet slots and the pin 39 is not needed. However a small screw or other cap 51 is placed over the plunger, such cap being threaded, as indicated at 52, to the protective cap 27. The plunger is made in two parts, a core member 53 and a shell member 54. Both members are flanged as indicated at 55 and 56. These members may be simply loosely telescoped or if desired secured together after being interfitted.

Inasmuch as the spring will force both members upwardly to the position indicated in Figure 9 it is not essential that the members be secured together. The shell member is only needed for depressing the core member. In this case the plunger is always unlocked and ready to be manipulated whenever the cap 51 is removed.

It is obvious that various changes and modifications may be made in the details of construction and design of the above specifically described embodiment of this invention without departing from the spirit thereof, such changes and modifications being restricted only by the scope of the following claims:

What is claimed is:—

1. In a fountain pen wherein the barrel forms the reservoir and having ink suction and expelling means including a collapsible nipple, a manipulating device for the nipple comprising a cap fitted to the fountain pen and over the nipple, the end of said cap being closed and provided with a centrally disposed opening of less diameter than the inner diameter of the body of the cap, a spring arm in the cap crimped near the top to provide a long leg and a short leg and a V-shaped fulcrum, the fulcrum adapted to bear on the wall of the opening in the cap in the extended position of the spring arm, and a plunger disposed for reciprocating motion through the opening in the cap and provided at its inner end with a recess adapted to receive the upper end of the spring arm.

2. In a fountain pen having ink suction and expelling means including a collapsible nipple, a manipulating device for the nipple comprising a cap fitted to the fountain pen and over the nipple, the end being closed and provided with a centrally disposed opening of less diameter than the inner diameter of the body of the cap, a spring arm in the cap crimped near the top to provide a long leg and a short leg and a V-shaped fulcrum, a plunger disposed for reciprocating motion through the opening in the cap and provided at its inner end with a recess adapted to receive the upper end of the spring arm, said plunger having in the body thereof a bayonet slot, and a pin passing transversely through the upper end of the cap and through the bayonet slot limiting the withdrawal of the plunger to maintain a slight bow in the spring and providing means for locking the plunger in depressed position.

GEORGE HOWARD OSTERHOUT.
